UNITED STATES PATENT OFFICE.

HENRY E. LE GENDRE, OF CRESSKILL, NEW JERSEY, AND GEORGE LEICH, OF NEW YORK, N. Y., ASSIGNORS TO E. W. BLISS COMPANY, OF BROOKLYN, NEW YORK, A CORPORATION OF VIRGINIA.

PNEUMATIC TOOL.

1,066,414.

Specification of Letters Patent.

Patented July 1, 1913.

Original application filed November 3, 1910, Serial No. 590,493. Divided and this application filed December 11, 1911. Serial No. 665,164.

To all whom it may concern:

Be it known that we, HENRY E. LE GENDRE and GEORGE LEICH, citizens of the United States, residing, respectively, at 5 Cresskill, in the county of Bergen and State of New Jersey, and in the borough of Brooklyn, county of Kings, city and State of New York, have invented certain new and useful Improvements in Pneumatic 10 Tools, of which the following is a specification.

This invention relates to a closure or locking-means for the ends of the casings of pneumatic tools, and aims to provide certain improvements therein.

It further relates to improvements in the general structure of such tools at the inlet end.

Pneumatic tools are ordinarily subjected 20 to a great amount and degree of vibration and it has been difficult to obtain a means for closing the end of the tool casing which will not be loosened under such vibration. The present invention is designed to overcome the foregoing objection, and provides 25 a closure which may not only be maintained fixed in the casing under vibration, but upon which the force of vibration acts to increase its fixity. The closure also acts as a means 30 for holding securely in place certain parts of the tool at the inlet end.

The present application is a division of our earlier application S. No. 590,493, filed November 3, 1910.

35 An embodiment of the invention is described in detail in connection with the accompanying drawings, wherein—

Figure 1 is a vertical sectional view of the end portion of a pneumatic tool, showing the end-closure in place. Fig. 2 is a 40 view in elevation of a part of the end closure, Fig. 3 is a view partly in elevation and partly in section of another part of the end closure, fitted upon the part shown in the preceding view. Fig. 4 a vertical sectional view of the valve-box, to show more clearly the construction thereof.

In the drawings, A indicates a casing having a piston cylinder A² therein and

which may also have a cylindrical chamber 50 A¹ therein in which a valve box or the like C may be contained. The valve box C has a valve-proper c therein and may be closed by a cap c¹ fitting within a recess c² on the upper face of the valve-box.

D and E indicate respectively, parts of the end-closing means, D a plug or cap for closing the end of the casing and E a nut for locking said plug in place. The plug D has a base portion d and a conical or tapering projection or extension d³, preferably ending in a squared end d⁴, by which the plug may be engaged by a wrench. The base portion d is also preferably provided with threads d' on its periphery by which it may engage threads a' upon the interior of the end of the casing A. The lower face of the plug may be recessed, as indicated at d², and trued so that it may fit tightly against the part which it engages, such as 60 the cap on the upper face of the valve box and prevent escape of motive-fluid. The plug thus not only acts as a closure for the end of the casing but also serves to hold the interior parts in place. The plug has a 65 passage d⁵ longitudinally therethrough, for admission of air to the tool, and is formed with interior screw-threads by which the end of a supply pipe is connected. Nut E is 70 of cylindrical form and has a tapered bore 75 c³ therein of approximately the same size as the tapered extension d³ of the plug D upon which extension the nut is adapted to fit. The nut is provided with threads e' for engaging the threads a' of the casing. The 80 nut is also preferably split, as at e, and is 85 preferably provided with squared faces c² whereby it may be engaged by a wrench.

The plug D is first inserted in the end of the casing in contact with the cap on the 90 valve-box, or other part against which it bears. The nut E is then placed over the plug and screwed down upon the plug. As the nut is screwed down upon the plug it is 95 expanded by the tapered extension thereof and its threads are thus wedged or expanded tightly into engagement with the thread on the casing. The plug is thus held se-

surely in position by the nut and the nut is firmly pressed by the plug into engagement with the casing. The plug being also preferably provided with screw-threads may be thus additionally secured in position. The closure will not be loosened by vibration, inasmuch as the force of vibration will only drive the plug and nut into closer contact, which will in turn expand the nut into 10 firmer contact with the casing.

Many modifications and changes may be made in the embodiment illustrated and described, without departing from the spirit of the invention.

15. What we claim is:—

1. An end closure for pneumatic tools, comprising a cap and an expansible nut, said cap being adapted to rest upon and be firmly supported by a part of a pneumatic tool, and said nut being adapted to press said cap upon said part by which it is supported and interacting means upon said nut and cap for expanding said nut when said nut is pressed upon said cap.

2. An end closure for pneumatic tools, comprising a cap and an expansible nut, said cap being adapted to rest upon and be firmly supported by a part of a pneumatic tool, and said nut being adapted to press said cap upon said part by which it is supported, said cap having a tapered part adapted to expand said nut when said nut is pressed upon said cap.

3. An end closure for pneumatic tools, comprising a cap and a split nut, said cap being adapted to rest upon and be firmly supported by a part of a pneumatic tool, and said nut being adapted to press said cap upon said part by which it is supported, said cap having a tapered part adapted to expand said nut when said nut is pressed upon said cap.

4. An end closure for pneumatic tools, comprising a cap and a split nut having a tapered opening therein, said cap being adapted to rest upon and be firmly supported by a part of a pneumatic tool, said nut being adapted to press said cap upon said part by which it is supported, and said cap having a tapered extension adapted to fit said tapered opening in said nut and expand said nut when said nut is pressed upon said cap.

5. In a pneumatic tool, a body, and an end closure comprising a cap having a tapered extension and a split threaded nut engaged by said tapered extension, both said cap and nut engaging said body, whereby shocks imparted to said tapered extension 50 drive said nut into binding engagement with said body.

6. An end closure for pneumatic tools, comprising a threaded cap and a threaded expansible nut, said cap being adapted to

be screwed down firmly upon a part of a 65 pneumatic tool, and said nut being adapted to maintain said cap in engagement with said tool part and interacting means upon said nut and cap for expanding said nut when said nut is pressed upon said cap. 70

7. An end closure for pneumatic tools, comprising a threaded cap and a threaded expansible nut, said cap being adapted to be screwed down firmly upon a part of a pneumatic tool, and said nut being adapted 75 to maintain said cap in engagement with said tool part, said cap having a tapered part adapted to expand said nut when said nut is pressed upon said cap.

8. An end closure for pneumatic tools, 80 comprising a threaded flanged cap, and a threaded expansible nut, said cap being adapted to be screwed down firmly upon a part of a pneumatic tool, and said nut being adapted to maintain said cap in engagement with said tool part, said cap having a tapered part adapted to expand said nut when said nut is pressed upon said cap.

9. In a pneumatic tool, a body having 90 an interiorly threaded opening in its end, an end closure comprising a cap, adapted to close the end of said body, having a screw-threaded flanged portion and a smooth tapered portion, the taper being 95 toward the upper portion of said cap, and a split externally threaded nut having a smooth correspondingly tapered opening therethrough fitting over said tapered portion of said cap, and adapted to be forced 100 into binding engagement with the threads on a pneumatic tool body by the interengagement of its tapered opening with the tapered portion of said cap.

10. In a pneumatic tool, a body having an 105 interiorly threaded opening in its end, an end closure comprising a cap, adapted to close the end of said body, having a screw-threaded portion and a tapered portion, and a split threaded nut having a tapered opening 110 therethrough fitting over said tapered portion of said cap, and adapted to be forced into binding engagement with the threads on a pneumatic tool body by the interengagement of its tapered opening 115 with the tapered portion of said cap.

11. In a pneumatic tool, the combination of a casing having a chamber therein, a valve mechanism contained within said chamber comprising a boxing separable 120 from the casing, a valve-proper movable within said boxing, and a cap, and a closure adapted to engage the end of said casing and retain said valve mechanism in place within the casing. 125

12. In a pneumatic tool, the combination of a casing having a chamber therein, a valve mechanism contained within said

chamber, a closure having a tapered shank and an inlet therethrough adapted to fit within the casing above said valve mechanism, and an expansible nut adapted to fit upon said tapered shank for locking said closure in place.

In witness whereof, we have hereunto

signed our names in the presence of two subscribing witnesses:
